UNITED STATES PATENT OFFICE.

JAMES LAROCCA, OF CICERO, ILLINOIS, ASSIGNOR TO ELECTRO-MAGNETIC TOOL COMPANY, OF CICERO, ILLINOIS, A CORPORATION OF ILLINOIS.

IMPACTING TOOL.

Application filed August 23, 1924. Serial No. 733,749.

My invention is a mechanical movement finding useful employment in various ways, the mechanism of my invention being of particular service when employed in the operating mechanism of an impacting tool.

The mechanism of my invention includes a rotatable carrier, a plunger carried thereby, means for moving the plunger to one position with reference to the carrier, an abutment positioned to be engaged by the plunger when in this position, and mechanism for effecting movement of the plunger with reference to the carrier to an alternative and abutment-escaping position consequent upon the engagement of the plunger and abutment. In the preferred embodiment of the invention a spring is employed to restore the plunger to that position upon the carrier in which the plunger is engageable with the abutment, which abutment may be the shank of a drill or rivet set. As the mechanism is preferably constructed, an electric motor and suitable transmission gearing are employed to rotate the carrier and strike the plunger upon the abutment. The plunger is desirably so related to the carrier and abutment that a side of the plunger strikes the abutment, the abutment escaping movement of the plunger being approximately at right angles to the abutment striking direction of the plunger. The spring serves as a flexible or resilient link or medium between the motor driven transmission gearing and the carrier, the spring thus functioning through the plunger. When the carrier is moved from rest after each impact, its speed is accelerated by the spring in which power is absorbed or stored for this purpose as the plunger is withdrawn from the abutment against the force of the spring. In the preferred embodiment of the invention the plunger and carrier rebound after striking the abutment, in a direction opposite to the abutment striking movement of the plunger and carrier. There is thus afforded a space between the plunger and abutment that permits the plunger to be withdrawn into the carrier by the motor to thereby escape the abutment as the plunger and carrier recover from the rebound, whereby wearing engagement of plunger and abutment is reduced.

The invention will be more fully explained in connection with the accompanying draw-

ing in which Fig. 1 is a side view, with a 55 casing cover removed, of the preferred form of my invention as embraced in an impacting tool; Fig. 2 is a sectional view on line 2-2 of Fig. 1; Fig. 3 is a sectional view on line 3-3 of Fig. 1 with parts shown in 60 full; and Fig. 4 is a view somewhat similar to Fig. 1 but showing a lesser portion, the carrier and plungers being shown withdrawn from the abutment, the carrier being also shown in section. 65

The operating shaft 1 may be driven by any suitable means. In the drawings I have illustrated an electric motor 2 brought into driving relation with this shaft through the intermediation of a spur pinion 3 upon the 70 motor shaft and a spur gear 4 upon the operating shaft. The operating shaft functions through any suitable means, such as a spur pinion 5 fastened upon the shaft by a pin 6. 75

The annular carrier 7 has a hub portion by which this carrier is journaled upon the shaft 1 to be capable of turning in the course of operation both with respect to and in the direction of this shaft and the pinion 5 fast 80 upon the shaft. The plunger mechanism is shown as including two plungers 8 and 9, each in the form of a rack in mesh with opposite sides of the common pinion 5. The invention, however, is not to be thus limited. 85 These racks are movable upon and travel bodily with the carrier. Springs 10, 11 are interposed between the carrier and racks and serve, when free to act, to place the racks in their outer positions defined by a suitable 90 stop such as the casing 14. An abutment 12 is positioned within the circle of rotation of the outer ends of the racks when these racks are in their outer positions, whereby the sides of the racks successively strike the 95 abutment as the carrier is given rapid intermittent turning movements in the direction of the shaft and pinion. The invention is illustrated as being embodied in an impacting tool in which the abutment is the butt 100 or striking end of a drill 13 which passes through a casing 14 that houses the carrier and other parts, to project into the interior of the casing. The drill has a shoulder formation 15 to limit the extent to which the 105 abutment will enter the casing and define the functioning position of the abutment. The motor 2 and the gearing 3, 4 may be

carried by the casing upon its exterior. For convenience the casing is formed with an extension 16 constituting a handle for the device if it is to be of portable and manipulatable form.

In operation, the shaft 1 is driven at a substantially constant speed by the motor, through the intermediation of the gearing 3, 4. Assuming the device to be in the stage 10 of operation illustrated, the pinion 5, fixedly coupled at 6 with the shaft, draws the racks or plungers 8, 9 inwardly against the force of the springs 10, 11 until the rack 9 escapes engagement with the abutment, whereupon 15 the springs force the racks rapidly outward to a point limited by the stop, in this instance the casing 14. The carrier and racks are thereafter turned until the side of the rack 8 at the outer end thereof strikes the 20 abutment 12 whereupon the rack 8 is operated upon and operates as described in the case of rack 9.

As I have embodied my invention, one 25 function of the springs is to place the plungers 8 and 9 in their outer, abutment striking, position upon and with respect to the carrier. A secondary function is to provide a flexible or resilient link or medium 30 between the driving motor and the driven carrier so that when the carrier is started from rest, as it is after each impact, the accelerating force is transmitted, absorbed or stored and gradually applied to the carrier by the springs. Now when the carrier 35 is rotating the plungers while in their outer positions at high tool operating speeds and a plunger strikes the abutment 12, the carrier and the plungers not only stop, but they rebound. The direction of the rebound being 40 against the direction of rotation of the pinion, the real velocity of the pinion in respect to the rack is the sum of the pinion's speed in one direction and the carrier's speed in the reverse direction. The result is that 45 the plungers or racks are pulled back into the carrier at the rate which is the sum of the pinion speed and the recoil speed and is very quick. The striking plunger in being pulled rapidly inward while in rebound, 50 escapes the abutment to prevent or lessen any dragging action or half hitting which spawls or drags over the metal of either or both of these elements if allowed. After 55 the springs have been compressed or rather while being compressed the carrier and the plungers are being accelerated by and in the direction of rotation of the pinion, and as the plungers approach the same speed as the pinion, the energy stored in the springs 60 acts to accelerate the carrier. The added accelerating force must give the carrier a speed in excess of the pinion speed and allow the springs to take their normal positions and the striking elements their normal 65 positions.

Changes may be made without departing from my invention.

Having thus described my invention, I claim:

1. The combination with a rotatable carrier; of a plunger carried thereby and coupled therewith; means for moving the plunger to one position with reference to the carrier; an abutment positioned to be engaged by the plunger when in this position; and mechanism, supplied in addition to the abutment and in actuating relation to the plunger, for effecting movement of the plunger with reference to the carrier to an alternative and abutment escaping position consequent upon the engagement of the plunger and abutment. 70

2. The combination with a rotatable carrier; of a plunger carried thereby and coupled therewith; means for moving the plunger to one position with reference to the carrier; an abutment positioned to be engaged by a side of the plunger when in this position; and mechanism, supplied in addition to the abutment and in actuating relation to the plunger for effecting movement of the plunger with reference to the carrier to an alternative and abutment escaping position consequent upon the engagement of the plunger and abutment. 75

3. The combination with a rotatable carrier; of a plunger carried thereby and coupled therewith; a spring interposed between the carrier and plunger for moving the plunger to one position with reference to the carrier; an abutment positioned to be engaged by the plunger when in this position; and mechanism, supplied in addition to the abutment and in actuating relation to the plunger, operating against the force of the spring for effecting movement of the plunger with reference to the carrier to an alternative and abutment escaping position consequent upon the engagement of the plunger and abutment. 80

4. The combination with a rotatable carrier; of a plunger carried thereby and coupled therewith; a spring interposed between the carrier and plunger for moving the plunger to one position with reference to the carrier; an abutment positioned to be engaged by a side of the plunger when in this position; and mechanism, supplied in addition to the abutment and in actuating relation to the plunger, operating against the force of the spring for effecting movement of the plunger with reference to the carrier to an alternative and abutment escaping position consequent upon the engagement of the plunger and abutment. 85

5. The combination with a rotatable carrier; of means for rotating the carrier; a yielding power transmitting element between the carrier and said means; an abutment; a plunger upon and coupled with the 90

carrier and positioned to engage the abutment; and mechanism, supplied in addition to the abutment and in actuating relation to the plunger, for effecting movement of the plunger with reference to the carrier to an alternative and abutment escaping position consequent upon the engagement of the plunger and abutment.

6. The combination with a rotatable carrier; of means for rotating the carrier; a yielding power transmitting element between the carrier and said means; an abutment; a plunger upon and coupled with the carrier and positioned thereon to have a side engage-
10 the abutment; and mechanism, supplied in addition to the abutment and in actuating relation to the plunger, for effecting movement of the plunger with reference to the carrier to an alternative and abutment es-
15 caping position consequent upon the engage-
20 ment of the plunger and abutment.

7. The combination with a rotatable carrier; of means for rotating the carrier; a power transmitting spring between the car-
25 rier and said means; an abutment; a plunger upon and coupled with the carrier and positioned to engage the abutment; and mechanism, supplied in addition to the abutment and in actuating relation to the
30 plunger, for effecting movement of the plunger with reference to the carrier to an alternative and abutment escaping position consequent upon the engagement of the plunger and abutment.

35 8. The combination with a rotatable carrier; of means for rotating the carrier; a power transmitting spring between the carrier and said means; an abutment; a plunger upon and coupled with the carrier and positioned thereon to have a side engage the abutment; and mechanism, supplied in addition to the abutment and in actuating relation to the plunger, for effecting movement of the plunger with reference to the carrier to an alternative and abutment escaping position consequent upon the engagement of the plunger and abutment.

9. The combination with a rotatable carrier; of a rack carried thereby; a driving pinion in mesh with the rack; means for moving the rack to one position with reference to the carrier; and an abutment positioned to be engaged by the rack when in this position, said pinion serving to move
50 the rack from abutment engaging position consequent upon the engagement of the rack and abutment.

60 10. The combination with a rotatable carrier; of a rack carried thereby; a driving pinion in mesh with the rack; a spring inter-
65 posed between the rack and carrier for moving the rack to one position with reference to the carrier; and an abutment positioned to be engaged by the rack when in this posi-
66 tion, said pinion serving to move the rack

from abutment engaging position against the force of the spring consequent upon the engagement of the rack and abutment.

11. The combination with a rotatable car-
rier; of a rack carried thereby; a driving 70 pinion in mesh with the rack; means for moving the rack to one position with refer-
ence to the carrier; and an abutment posi-
tioned to be engaged by a side of the rack
when in this position, said pinion serving to 75 move the rack from abutment engaging
position consequent upon the engagement of
the rack and abutment.

12. The combination with a rotatable car-
rier; of a rack carried thereby; a driving 80 pinion in mesh with the rack; a spring inter-
posed between the rack and carrier for
moving the rack to one position with refer-
ence to the carrier; and an abutment posi-
tioned to be engaged by a side of the rack 85
when in this position; said pinion serving
to move the rack from abutment engaging
position against the force of the spring con-
sequent upon the engagement of the rack
and abutment.

13. The combination with a rotatable car-
rier; of a plunger carried thereby and cou-
pled therewith; means for moving the plunger
to one position with reference to the car-
rier; an abutment positioned to be en-
gaged by the plunger when in this position,
said plunger rebounding from the abutment;
and mechanism, supplied in addition to
the abutment and in actuating relation to
the plunger, for effecting movement of 100
the plunger with reference to the carrier
toward an alternative and abutment escap-
ing position consequent upon the engage-
ment of the plunger and abutment and while
the plunger is out of engagement with the 105
abutment in rebounding therefrom.

14. The combination with a rotatable car-
rier; of a plunger carried thereby and cou-
pled therewith; means for moving the plunger
to one position with reference to the car-
rier; an abutment positioned to be engaged
by a side of the plunger when in this posi-
tion, said plunger rebounding from the
abutment; and mechanism, supplied in addition
to the abutment and in actuating rela-
tion to the plunger for effecting movement
of the plunger with reference to the carrier
toward an alternative and abutment escap-
ing position consequent upon the engage-
ment of the plunger and abutment and while
the plunger is out of engagement with the 120
abutment in rebounding therefrom.

15. The combination with a rotatable car-
rier; of a plunger carried thereby and cou-
pled therewith; a spring interposed between 125
the carrier and plunger for moving the
plunger to one position with reference to the
carrier; an abutment positioned to be en-
gaged by the plunger when in this position,
said plunger rebounding from the abutment;

- and mechanism, supplied in addition to the abutment and in actuating relation to the plunger, operating against the force of the spring for effecting movement of the plunger with reference to the carrier toward an alternative and abutment escaping position consequent upon the engagement of the plunger and abutment and while the plunger is out of engagement with the abutment in rebounding therefrom.
16. The combination with a rotatable carrier; of a plunger carried thereby and coupled therewith; a spring interposed between the carrier and plunger for moving the plunger to one position with reference to the carrier; an abutment positioned to be engaged by a side of the plunger when in this position, said plunger rebounding from the abutment; and mechanism supplied in addition to the abutment and in actuating relation to the plunger, operating against the force of the spring for effecting movement of the plunger with reference to the carrier toward an alternative and abutment escaping position consequent upon the engagement of the plunger and abutment and while the plunger is out of engagement with the abutment in rebounding therefrom. 20 25
- In witness whereof, I hereunto subscribe my name.
- JAMES LAROCCA.
